UNITED STATES PATENT OFFICE.

LEONARD B. BERRIEN, OF MOLINE, ILLINOIS.

TYPE-WRITING MACHINE.

SPECIFICATION forming part of Letters Patent No. 513,476, dated January 30, 1894.

Application filed April 23, 1892. Serial No. 430,429. (No model.)

To all whom it may concern:

Be it known that I, LEONARD B. BERRIEN, a citizen of the United States, residing at Moline, in the county of Rock Island and State of Illinois, have invented certain new and useful Improvements in Type-Writing Machines, of which the following is a specification, reference being had to the accompanying drawings, in which—

10 Figure 1 is a top or plan view. Fig. 2 is a side elevation, some parts being in section. Fig. 3 is a central vertical cross section. Fig. 4 is a partial sectional view on line 4—4 of Fig. 1, showing the paper carriage. Fig. 5 is 15 an enlarged detail, being a top or plan view of the dog which shifts the paper carriage. Fig. 6 is a similar view, showing the dog in a different position. Fig. 7 is a side elevation of the inking device. Fig. 8 is an enlarged 20 detail, being a front elevation of a portion of the letter rack, showing the device for adjusting the rack for printing capital letters; and Figs. 9 and 10 are enlarged details, being side elevations of the paper cylinder; showing 25 the paper holding bar in different positions. Fig. 11, is a detail showing the shaft carrying the type disks and the manner of mounting the same.

My invention relates to typewriters, and its 30 object is to provide a new and improved typewriter which will be simple and inexpensive in construction and efficient in operation. I accomplish this object as hereinafter specified and as illustrated in the drawings.

35 That which I regard as new will be pointed out in the claims.

In the drawings,—11, indicates the base board, which may be made of any suitable material, and is adapted to carry the various 40 parts of the typewriter. It may be made of any desired shape, but I prefer to make it rectangular, as shown.

45 12, 13, indicates standards which are rigidly secured at opposite sides of the base board 11, and are provided with suitable bearings in their upper ends.

14 indicate a board, preferably rectangular in shape, which is provided at each end with a pivot 15. The pivots 15 are adapted 50 to fit into the bearings in the standards 12 and 13, as shown in Fig. 1, and are placed to the rear of the center of the board 14, so that

the front edge of the board may be tilted downward, for purposes which will be herein-after set forth. The board 14 is marked off 55 into spaces, on which are marked the different letters of the alphabet and other symbols or signs which are usually used in typewriting. (For convenience, this board 14 will be hereinafter referred to as the letter board.) 60 I prefer to draw a line extending centrally the length of the board, so as to divide it longitudinally into two sections, as shown in Fig. 1, and to place the letters and symbols as shown; the object of which arrangement will 65 be more fully hereinafter set forth.

16, indicates a rack which is secured to the front edge of the letter board 14 in any suitable manner. The teeth of the rack lie along the upper edge of the board 14, and are angular, as shown in Fig. 8. The rack 16 is so arranged that the angle of the spaces between the teeth will lie opposite the checks or spaces marked off on the letter board 14, as shown in Fig. 1. I prefer to cast the rack 70 16 with a plate 17, extending at right angles thereto, as shown in Fig. 2, upon which plate 17 the letter board 14 is secured; but I do not wish to limit myself to this construction.

It is understood that the letter board 14 80 need not necessarily be of wood, but may be made of any other suitable material. When the plate 17 is used, the pivots 15 may be cast upon it, as that would be a more convenient way of securing them in place, but they may be secured to the letter board 14 if desired. If desired, the plate 17 may be so shaped as to dispense altogether with the letter board 14, the letters in that case being marked upon the upper surface of the plate 17. 90

18 indicates a stop which is secured to the plate 17 and projects downward in such a position as to prevent accidental contact of the type with the paper when a space is made by means of the spacing key, as hereinafter described.

19 indicates a lever, which is rigidly connected to the inner edge of the letter board or to the plate 17, and projects upward therefrom at about right angles thereto. It is 100 preferably located at the central point of the board to which it is attached. The use of the lever 19 will be hereinafter set forth.

20 and 21 indicate two standards, which

are rigidly secured upon the base board 11 near the rear of the central portion thereof as best shown in Fig. 1, and a short distance apart. Pivoted on pivots 22 and 23, which are supported by the standards 20 and 21, is a swinging frame α , in which is a shaft 24, which is normally in a substantially vertical position, as shown in Fig. 11. Depending from this frame α is a lug or pin b whose function is hereinafter described. By mounting the shaft 24 upon pivots between the standards 20 and 21, it may be tilted in the direction indicated by the arrow in Fig. 2, for purposes which will be hereinafter set forth.

25 indicates a bar or plate which is connected to the frame α , and extends to the front and rear thereof, as shown in Fig. 3. The forward end of the bar 25 is connected to a bent lever 26, the forward end of which is bent upward and is pivotally connected to the lever 19 near its upper end, as shown in Figs. 2 and 3. By this construction, when the forward edge of the letter board 14 is depressed, the upper end of the lever 19 will be thrown forward, thereby pulling the lever 26 forward, as indicated by the arrow in Fig. 3, and thereby causing the shaft 24 to tilt, as shown in Fig. 3. When the downward pressure upon the letter board is removed, it will return to its horizontal position, thereby reversing the motion of the lever 26 and returning the shaft 24 to a vertical position.

27, indicates a sleeve which is mounted upon the shaft 24, the lower end of which sleeve bears upon the upper surface of the bar 25, the bar 25 being finished off to present a smooth surface to receive the lower end of the sleeve 27. The upper end of the sleeve 27 terminates near the upper end of the shaft 24, as best shown in Fig. 3.

28, indicates a type disk, which is mounted upon the upper end of the sleeve 27, and is secured thereto by a set-screw or in any other suitable manner, so that it will rotate with the sleeve. Types of a number of the letters of the alphabet are placed upon the periphery of the disk 28. When the letters are arranged upon the letter board 14 as shown in Fig. 1, the types upon the disk 28 would represent the letters and symbols upon the right hand side of the letter board, except that both small and capital letters would appear on the disk, as indicated in Fig. 2, small letters being placed beside corresponding capital letters.

29, indicates an ink pad which is secured upon the upper surface of the disk 28, as best shown in Fig. 3.

30, indicates a gear wheel, which is mounted upon the lower end of the sleeve 27 and is secured thereto by a set screw 31 or in any other suitable manner, so that it will rotate with the sleeve 27.

32, indicates a sleeve, which is mounted upon the sleeve 27 above the gear wheel 30, as best shown in Fig. 3, a washer 33 being in-

terposed between the wheel 30 and the sleeve 32. The sleeve 32 extends upward and preferably terminates a short distance below the disk 38, a washer 34 being interposed between the upper end of the sleeve 32 and the hub of the disk.

35 indicates a second type disk, which is mounted upon the sleeve 32 and is rigidly secured thereto so as to rotate therewith. The disk 35 is placed immediately under the disk 28, sufficient space being left between them to permit of their rotation independently of each other.

36 indicates a gear wheel which is connected to or formed upon the sleeve 32 near its lower end, as shown in Fig. 3. The wheel 36 is substantially similar to the wheel 30. In the drawings I have shown the type disk 35, sleeve 32 and gearwheel 36 as being formed integral with each other, but I do not wish to limit myself to this construction, as they may be made separate if desired, or the disk and sleeve may be made integral with each other and the wheel 35 be secured to the sleeve, or they may be arranged in various other ways. The arrangement of the type disks and gear wheels 30 and 36 is such that when the gear 30 is rotated the disk 28 will be correspondingly rotated, and similarly, when the wheel 36 is rotated the disk 35 will be rotated in a similar direction. When the shaft 24 is tilted, as hereinbefore described, the type disks 28 and 35 will also be turned to an inclined position, as shown in Fig. 3, for purposes which will be hereinafter set forth.

37, 38, indicate standards which are rigidly secured to the base board 11 at opposite sides, and extend upward therefrom.

39 indicates a rod or bar which is rigidly secured between the standards 37 and 38 near their upper ends.

40 indicates a rod or bar similar to the rod 39, which is also secured between the standards 37 and 38 at a point below and slightly forward of the bar 39, as shown in Fig. 3.

41 indicates a frame, which is about half the length of the letter board 14, and is provided with a forwardly extending lever 42 at one end. The lever 42 is provided with a finger-plate 43, which is preferably circular in form, and is adapted to receive a finger of the operator. The frame 41 is provided with rollers 44 and 55, which rollers are adapted to move upon the rod 39. By this means the frame 41 may be moved transversely of the base board 11, as desired.

45 indicates a rack frame which is pivotally secured to the frame 41 and extends rearward and downward therefrom, as shown in Fig. 2. The rear edge of the frame 45 is provided with teeth, which are adapted to mesh with the cogs of the gear wheel 36 in such manner that when the frame 41 is moved transversely of the base board, the gear wheel 36 will be rotated in a corresponding direction.

46, indicates a plate which is secured to the

under side of the rack frame 45, and projects rearward therefrom to a short distance under the gear wheel 36. By this construction, when the rack frame 45 is raised, as will be hereinafter described, the gear wheel 36 will also be moved upward on the sleeve 27, for purposes which will be hereinafter set forth.

47 indicates a stiff spring, the upper end of which is rigidly connected to the frame 41 10 and the lower end of which extends under the rack frame 45 and bears against its under surface, as shown in Fig. 3. The object of the spring 47 is to provide for the lifting of the rear edge of the rack frame 45 when the frame 41 is tilted, as by reason of the fact that the rack frame 45 is pivotally connected to the frame 41, it would not otherwise be lifted.

48 indicates a second frame which is in general similar to the frame 41, being provided with rollers 49, 50, which are adapted to rotate on the bar 40, and with a lever 51 which projects forward from one end of said frame. The lever 51 is provided with a finger piece 52 similar to the finger piece 43. The lever 51 is placed on the outer end of the frame 48.

53 indicates a rack frame, which is in many respects similar to the rack frame 45, and is pivotally connected to the frame 48. The teeth of the rack frame 53 are adapted to mesh with the teeth of the gear wheel 30, as shown in Fig. 3.

54 indicates a curved bar, which projects downward and forward from the frame 48 in such manner as to partially encircle the rod 40 and thereby prevent the rollers 49 and 50 from leaving the rod 40 when the frame 48 is tilted. The rods 39 and 40 are at such a height above the letter board 14 as to hold the levers 42 and 51 a short distance above the rack 16, so that they may be moved freely across the board.

By pressing downward upon the levers 42 45 and 51, they may be made to fit into the notches between the teeth of the rack 16, and by further downward pressure the rack 16 will be tilted downward to the position shown in Fig. 3, thereby effecting the tilting of the shaft 24 and consequently the throwing of the type disks to the rear. When the levers 42 and 51 are moved, the rack bars carried by them will rotate the respective gears in a similar direction, thereby rotating the type disks 50 in a similar direction. When one of the levers, as 51, is stopped over one of the spaces in which is marked a character, as for instance, the number "2," the position of the type disk 28 which is operated by such lever 55 would be so arranged that the type "2" carried by such disk will be thrown in position to come in contact with the paper to be written on. By pressing downward upon the lever 51, it will enter the notch in the rack 50 which is opposite such space, and will be held 60 from moving out of its position. Further

downward pressure upon the lever will tilt the letter board and rack, thereby throwing the disk 28 to the rear. As will be more fully hereinafter described, the paper is carried upon a cylinder back of the disk 28, and in such position that when the disk is tilted, as shown in Fig. 3, the type which is opposite the cylinder will be forcibly brought into contact with the paper and the letter thereby printed thereupon. The type disk 28 is normally in position to strike the paper when the shaft 24 is tilted. The type disk 35, being below it, will consequently not come into contact with the paper under ordinary circumstances. When, however, the lever 42 is operated, which lever operates the gear 36 and the type disk 35, the downward movement of the lever will throw the rack 45 upward, thereby moving the gear 36 upward and 85 throwing the type disk 35 upward also, into the position formerly occupied by the type disk 28. When the shaft 24 is now tilted, one of the types upon the type disk 35 will come into contact with the paper. In order to limit the upward motion of the type disks a block 56 is provided, which is screwed upon the upper end of the shaft 24, which shaft is suitably screw threaded for that purpose. A screw 57 is screwed into the upper end of the block 56 until it comes in contact with the upper end of the shaft 24. The block 56 serves as a stop to limit the upward motion of the disks 28 and 35. By unscrewing the screw 57, the position of the block 56 may be adjusted as desired.

The type-disks 28 and 35 are so mounted upon the shaft 24 that normally only small letters or certain symbols will be printed. As has been hereinbefore described, the capital letters are placed beside their respective small letters, and in order to print capitals it is therefore necessary that the type disks should be turned a little more or less than usual in order to bring the capital letters in position for printing. I accomplish this extra rotation of the type disks by a lateral shifting of the letter board 14, which is accomplished as follows: As above described, the letter board is mounted in pivots 15 supported by the standards 12 and 13. The pivots 15 are made somewhat long, so that they may be moved in their bearings in the standards 12 and 13, whereby the letter board may be slightly shifted transversely of the base board. 115 On the under side of the plate 17 are provided two lugs 58 and 59, placed close together so as to form a suitable slot or recess.

60, indicates a lever which is provided with three arms 61, 62 and 63, the arms 62 and 63 resting in a nearly horizontal position upon the base board 11, depending on the position of the lever, and the arm 61 extending vertically upward. The upper end of the arm 61 is fitted into the recess formed by the lugs 120 58 and 59. The lever 60 is pivoted at its lower end upon a shaft 64, mounted between suit-

able standards 65 and 66 in such position that it may be rocked transversely of the base board.

67 indicates a spring, one end of which is rigidly secured to the board 11 and the other end is adapted to bear upon the upper surface of the arm 63 of the lever 60 in such manner as to hold such arm in contact with the base board. The opposite arm 62 of the lever 60 is thereby caused to lie a short distance above the base board, as shown in Fig. 8, and the rack 16 is held in such position that when one of the operating levers rests in one of the notches, the type disks will be in position to print small letters. By depressing the arm 62 of the lever, the rack 16 will be shifted transversely of the board 11, thereby also shifting the operating lever which is inserted in one of the notches, and moving its rack frame so as to rotate the corresponding type disk half a space, or to such position that the capital letter corresponding to the small letter which it is desired to print, will be moved to a position opposite the paper cylinder. The arm 62 is operated by means of a lever 68, the free end of which rests upon the upper side of said arm; as best shown in Fig. 8. The other end of the lever 68 is pivotally mounted in a suitable bearing 69, and is connected by means of a lever 70 to a finger board 71, which extends parallel with the letter board 14 and a short distance in front of it, as best shown in Fig. 1.

72, indicates a second lever, which is connected to the finger board 71 and is pivoted in suitable bearings 73, as shown in Fig. 1. By pressing downward upon the finger-board 71, the arm 62 will be depressed and the finger board and rack 16 will be correspondingly shifted. The finger board 71 preferably extends about half way across the typewriter, but if desired it may be made to extend entirely across. I prefer to make the levers 68 and 70 out of a single continuous wire bent to suitable shape, but I do not wish to limit myself to that construction.

The paper to be written upon is carried by a cylinder 74, which is mounted in suitable bearings 75 and 76 formed in a carriage 77, as best shown in Fig. 4. The carriage 77 is provided at its upper end with rearwardly projecting brackets 78 and 79, in which is mounted a rod 80 which extends transversely of the board 11, as best shown in Fig. 1. The lower edge of the carriage 77 is notched to form rack teeth 81, as best shown in Fig. 4, the object of which rack teeth will be explained more fully hereinafter.

82 indicates guides which are adjustably secured to the rod 80 by set screws e, and extend under and around the under portion of the cylinder 74, to serve as guides for the paper so that it may be readily placed upon the cylinder, by adjusting the said guides 82 toward or away from the cylinder to permit the paper to pass more or less freely around it.

83 indicates a rod which extends longitudinally of the cylinder 74, and is pivotally supported at its ends in bearings upon the carriage 77. Said rod is movable laterally in its bearings and is provided with a projecting end 84, which engages the adjacent end of the shaft 93 upon which the cylinder is mounted. The rod 83 is so shaped that, when it is moved laterally and its projecting end disengaged from the shaft 93, it may be turned out of contact with the surface of the cylinder to permit of the insertion of paper and then turned back into close contact with the cylinder to hold the paper firmly in position, and locked in place by being moved laterally into engagement with the shaft 93.

85 indicates a roller, a number of which are secured to the rear of the lower portion of the carriage 77, and are adapted to run upon a rail 86 suitably mounted upon the board 11. By this means the carriage 77 is prevented from swinging or being moved out of place.

87 indicates a plate which is secured to the rear portion of the brackets 78 and 79 said plate having an inclined position, as best shown in Fig. 2. The plate 87 is provided with a flange 88 at its upper edge, which is adapted to fit over the upper edge of an inclined plate 89 rigidly secured upon the board 11. The construction is such that the plate 87 will slide upon the plate 89 transversely of the typewriter, to shift the carriage 77 from one side to the other. Instead of a single plate 87, a number of plates may be provided, connected at suitable points to the carriage.

90 indicates an adjusting screw which is mounted in the plate 89, the end of which bears against the inner side of the plate 87. By screwing the screw 90 in or out the paper cylinder will be thrown toward or away from the type disks and the angle at which the type will strike the paper will be regulated. By adjusting the said screw the type may be made to strike the paper squarely giving a clear impression.

91 indicates a wheel which is mounted upon a sleeve 92, which sleeve fits upon a shaft 93 upon which the cylinder 74 is mounted.

94 indicates a binding screw which passes through the sleeve 92 and keys it to the shaft 93. By turning the wheel 91, the cylinder 74 may be rotated.

95 indicates a cogged wheel which is mounted upon the inner end of the sleeve 92, as best shown in Fig. 1.

96 indicates a spring pawl which is mounted upon the rod 80 and extends forward and upward and bears upon the periphery of the wheel 95, as shown in Fig. 1. The free end of the pawl 96 is adapted to fit into the notches in the wheel 95, and serves to hold the wheel in a stationary position except when the wheel 95 is rotated by rotating the sleeve 92 by means of the wheel 91. By this means the cylinder 74 is prevented from rotating except when rotated by the operator. The teeth of the wheel 95 are placed at such a distance

apart as to leave sufficient space between the lines of the paper to be written upon.

The carriage 77 is moved transversely of the board 11 by means of a dog 97, the shape 5 of which is best shown in Figs. 5 and 6. The dog 97 is mounted upon the board 11, as shown in Fig. 1, and is adapted to be moved at right angles to the cylinder 74 and carriage 77, as indicated in Figs. 5 and 6. The rear end of 10 the dog is provided with teeth 98 and 99, as best shown in Figs. 5 and 6, which project therefrom forming a recess 100, the inner surface of which is inclined, as shown. The tooth 98 is adapted to fit into the spaces between the rack teeth 81, as best shown in 15 Fig. 5.

101, indicates a pin rigidly secured to the board 11 in the recess 100, which pin is adapted to engage the inclined inner edge of such 20 recess, as shown.

102 indicates a slot formed in the dog 97, which slot is adapted to receive a pin *b* depending from the frame *x* in which the shaft 25 24 is supported, as shown in Figs. 5 and 6.

25 The slot 102 extends a short distance lengthwise of the dog 97, so as to permit moving the dog without moving the pin *b*.

102 indicates a second slot which is formed in the forward end of the dog 97.

30 104 indicates a pin which projects upward from a rod 105 and is fitted into the slot 103. The rod 105 extends to the front of the board 11, and is connected to a bar 106, as best shown in Fig. 1. The bar 106 extends across 35 the front edge of the board 11 for about half the width of the board, and preferably on the right hand side of the board, and then passes through a suitable opening in the board to the under side of it, and is pivoted on the under side of the board upon a suitable pivot 107, as indicated by dotted lines in Fig. 1. By this means the rod 106 may be moved in 40 the direction indicated by the arrow in Fig. 1 and in the opposite direction, to operate the 45 dog 97.

50 108 indicates a spring, one end of which is secured to a suitable support 109 mounted upon the board 11, and the other end of which is connected to the forward end of the dog 97, as best shown in Figs. 5 and 6. The spring 108 is curved, as shown, and is adapted to exert a backward pressure on the dog 97, and also when compressed to throw the forward end of the dog 97 in the direction indicated.

55 by the arrow in Fig. 6, thereby throwing the rear end of the dog 97 in the opposite direction, the lower end of the shaft 24 acting as a pivot. When the dog 97 is in its normal position, the spring 108 being then expanded, 60 the tooth 98 will lie between two of the teeth 81 of the rack carried by the carriage 77. When the bar 106 is moved in the direction indicated by the arrow in Fig. 1, or forward toward the forward edge of the board 11, the 65 dog 97 will be thrown to the position shown in Fig. 6, the tooth 98 being then withdrawn

from the rack, and such tooth will be thrown into contact with the pin 101, the rear end of the dog 97 being thrown to the right, as hereinbefore described. When the pressure upon 70 the bar 106 is released, the spring 108 will act to return it to its former position and will force the dog 97 backward. Instead of moving into the same notch from which it was withdrawn, however, the fact that it 75 has moved sidewise, as above described, will cause it to enter the next succeeding notch of the rack, and as the dog 97 moves backward the pin 101 sliding on the inclined surface of the recess 100 will cause the rack and carriage 80 77 to be moved sidewise a distance equal to the width of one space of the rack. The recess 100 and pin 101 are so arranged with relation to each other that they will be adapted to operate as described. By this 85 means the carriage will be shifted in order to present a space upon which the next succeeding letter is to be printed.

When the shaft 24 is tilted to the position shown in Fig. 3, as is the case when a letter 90 is printed, the lower end of the shaft will be thrown forward and such action will cause an operation of the dog 97 similar to that described when the bar 106 is operated. By this means, after each letter has been printed, 95 the carriage will be shifted the distance of one space. The bar 106 is intended for use for spacing between words and for other spacing when it is not desired to print.

It will be noticed that when the dog 97 is 100 moved backward in the act of spacing, the pin marked *b* in Figs. 3 and 6 will be free to move in the slot 102, and the weight of the type disks will have a tendency to cause the shaft 24 to tilt, throwing the type disks toward 105 the paper cylinder or platen. This tilting of the shaft cannot take place without causing the letter board to tilt, as shown in Fig. 3, and if there were nothing to limit the downward motion of the letter board the type 110 would strike the paper and a letter would be printed every time a space was made. Of course it is necessary that in writing the letter board should be tilted downward sufficiently to cause the type to strike the platen. 115 In order to regulate the tilting of the letter board, the rod 105 is provided with an upward projection *c* in Fig. 2, which, when the rod 105 is thrown outward as in spacing, will occupy the position indicated in dotted lines 120 in Fig. 2. When in the latter position the projection *c* will be near the lower end of the rod 18, and a slight tilting only of the letter board will cause them to come into engagement with each other, thereby preventing further tilting. When the rod 105 is in its normal position, the projection will be in the position shown in full lines in Fig. 2 and the rod 125 18 will not engage it until the letter board is tilted sufficiently to cause the type disks to 130 strike the platen.

110 indicates a bell which is mounted upon

a suitable standard 111 in front of the carriage 77, and near one end thereof, the standard 111 being mounted upon the board 11.

112 indicates a spring hammer which is supported by a bracket 113 carried by the carriage 77. The arrangement is such that when the carriage 77 has moved a greater part of the distance across the board 11, the end of the hammer 112 will be engaged by the upper portion of the standard 111, and thereby moved upward, putting it under tension, and as soon as the carriage has moved far enough to cause the free end of the hammer 112 to pass beyond the standard 111, it will be released and will strike the bell 110, thereby indicating that the carriage should be returned to its position on the other side of the board, substantially as is the case with other typewriters.

114 indicates an inking roller which is mounted upon a pivoted arm 115 carried by a bent lever 116, as best shown in Fig. 7. The lever 116 is pivoted upon the upper portion of a bar or bracket 117, which in turn is supported by the standard 21, as best shown in Fig. 7.

118 indicates a bar which is pivotally connected to the standard 21 and projects upward, and is connected to the lower arm of the lever 116, as shown in Fig. 7.

119 indicates a spring which is mounted upon a pin 120 upon the lever 116, and bears upon a lug 121 formed upon the upper part of the arm 115 in such manner as to exert a downward pressure upon said arm, whereby the roller 114 will be held with greater or less pressure upon the pad 29 and the type. The lower end of the bar 118 is rigidly connected to the swinging frame α , hereinbefore described, and I prefer to form it integral therewith, but do not wish to limit myself to that construction. When the shaft 24 is tilted, the swinging frame α will be moved backward or forward and the bar 118 correspondingly operated. This will throw the upper end of the lever 116 backward or forward, moving the roller 114 upon the pad 29.

The arrangement of the various parts is such that when the shaft 24 is in a vertical position and the type disks are consequently out of contact with the paper to be written upon, the bar 118 will be in a substantially vertical position and the roller 114 will rest upon the type of the upper type disk which is nearest the cylinder 74. When the shaft 24 is tilted, as in operating the machine, the roller 114 will be moved upward onto the pad 29, thereby exposing the type. The type will be inked by the roller 114 just prior to the time when the type is thrown into contact with the paper. The roller 114 does not touch the type disk until the disk has moved backward slightly, and therefore does not prevent its free rotation. When the type on the lower type disk are used, as above described, lower type disk will be moved upward so that the type to be used will be inked by the ink-

ing roller, substantially in the same manner as that above described. By this construction, each type is always freshly inked before it is used.

To operate the machine, paper is placed upon the cylinder 74 and the carriage is generally moved to the extreme right hand side of the board 11. Two of the fingers of the operator are placed in the finger pieces 43 and 52, and the type disks are rotated to bring the proper types into section by moving the frames 41 and 48 across the board, as hereinbefore described. To space, the bar 106 is operated by one or more of the fingers of the right hand. Capitals are made by pressing the finger board 71 with the fingers of the left hand. If, for instance, it were desired to print the small letter "w," the right hand frame 48 would be moved so that the lever 51 would fit into the space in the rack 16 opposite the letter "w" indicated on the letter board. The lever 51 would then be pressed downward, pressing downward the outer edge of the letter board and the rack 16. The type of the small letter "w" is so located upon the upper type disk that when the frame 48 is in the position described such small letter will be in position to strike the cylinder 74. Downward pressure upon the letter board would cause the type disk to be thrown backward, and the desired letter would be thrown into contact with the paper on the cylinder 74. To print the capital letter "W," by pressing the finger board 71 before the letter board 14 was pressed downward, as above described, the rack 16 would be shifted sidewise half a space and the capital letter "W" would be brought into proper position for printing. All the letters are printed in substantially the same way, except that some are printed by the lever 42 and some by the lever 51, depending on their position.

The object of dividing the letter board longitudinally, as shown in Fig. 1, is to permit of arranging the letters and symbols on the letter board so that the method of writing any small letter, capital letter or symbol may be readily understood. When the type are arranged on the disks as shown in Fig. 2, all small letters are written by tilting the letter board without shifting it laterally, as are also all symbols which are marked in the spaces along the front edge of the letter board. All capital letters are printed by shifting the letter board laterally and then tilting it, and all symbols which are marked in the spaces along the rear edge of the letter board are similarly written. In order that the eye may more readily pick out any desired letter, however, I have marked the spaces by arranging the letters alternately in the front and rear sections, and have used capital letters for marking; but that is merely for convenience, as above described, and I do not wish to limit myself to this arrangement. Neither do I wish to limit myself to arranging the rack 16 so that the notches will be opposite the dif-

ferent sections of the letter board, although I prefer that arrangement. If desired, however, instead of arranging the rack with its notches opposite the spaces of the letter board, 5 it could be placed so that the teeth of the rack would lie opposite the sections of the letter board, and the under sides of the levers 42 and 51 could be notched or suitably arranged so that they would fit upon the teeth 10 of the rack, as this construction would be the full equivalent of the arrangement shown.

That which I claim as my invention, and desire to secure by Letters Patent, is—

1. In a typewriter, the combination with 15 two transversely movable frames, of two type disks, and devices operated by said transversely movable frames to rotate said type disks, substantially as described.

2. In a typewriter, the combination with 20 independent transversely movable frames, of a paper cylinder, independent type disks adapted to come into contact with said paper cylinder, and means for rotating said type disks by the movement of said frames, substantially as described.

3. In a typewriter, the combination with independent transversely movable frames, and racks carried thereby, of independent type disks adapted to be rotated, and gear wheels 30 adapted to rotate with said type disks and to intermesh with the racks carried by said transversely movable frames, substantially as and for the purpose specified.

4. The combination with a transversely 35 movable frame and a paper cylinder, of a tilting and rotating type disk carrying type, devices operated by said transversely movable frame for rotating said type disk a tilting letter-board, mounted independently of the type 40 disk, a device connected with said letter board and said type disk, whereby the type disk is tilted upon the tilting of the letter board, and means for inking the type on the type disk, substantially as described.

5. The combination with a transversely 45 movable frame 41, a bracket for supporting said frame, and a rack frame 45 secured to said frame 41, of a tilting and rotatable type disk, a sleeve 32 secured to said type disk, 50 and a gear wheel mounted upon said sleeve and adapted to intermesh with said rack frame, whereby by the movement of said frame 41 the type disk will be rotated, a tilting letter board, mounted independently of the type 55 disk, a device connected with said letter board and said type disk, whereby the type disk is tilted upon the tilting of the letter board, substantially as described.

6. In a typewriter, the combination with a 60 paper cylinder, of a shaft pivotally mounted in a vertical position, a type disk rotatably mounted thereupon, type carried by said disk, an ink pad over said disk, a roller adapted to ink the type on said disk, and means for tilting said shaft to cause the type on said disk to come in contact with said paper cylinder, substantially as described.

7. In a typewriter, the combination with paper-holding devices, of a shaft pivotally mounted in a vertical position in front of said 70 paper-holding devices, a type disk carried by said shaft, type mounted thereupon, an ink pad over said type disk, a roller adapted to roll over said ink pad and to ink each type immediately before it is used, and means for 75 rolling said roller over said ink pad and over the type, substantially as described.

8. The combination with a shaft 24 adapted to be tilted, means for tilting said shaft, a type disk 29 mounted on said shaft, means for rotating said type disk, type carried by said type disk, and an ink pad over said disk, of a roller 114, a pivoted arm 115 supporting said roller, a lever 116 for supporting said arm 115, said lever 116 being pivotally supported near 85 said type disk, and a pivoted bar 118 connected to said lever 116 and to the shaft 24, whereby when the shaft is tilted the roller 114, will be moved upon said ink pad, and when the shaft is returned to a vertical position the 90 roller will rest over one of the types carried by the type disk, substantially as and for the purpose specified.

9. The combination with a pivoted shaft mounted in a vertical position, and means for tilting said shaft, of independent type disks mounted upon said shaft and adapted to rotate thereupon, types carried on the peripheries of said disks, means for rotating said type disks, a paper carrier placed near said 100 type disks in such manner that when said shaft is tilted one of the types on one of the disks will come in contact with the paper carried by said paper carrier, and means for moving one of said type disks vertically to 105 throw the type carried by said disks into position to strike the paper carried by said paper carrier when the shaft is tilted, substantially as described.

10. In a typewriter, the combination with a paper carriage, of a shaft vertically mounted opposite said carriage, a rotatable type disk mounted upon said shaft, a letter board mounted independently of the type disk and adapted to be tilted, a transversely movable 115 frame, means for rotating said type disk by the movement of said frame, devices for tilting said letter board, and a lever connected with said letter board and with the shaft carrying the type disk and operated by the tilting of said letter board to bring the type disk into contact with the paper carriage, substantially as described.

11. The combination with a paper carriage, 125 a letter board adapted to be tilted, said letter board being marked off into sections in which are placed the letters of the alphabet and other symbols, a rack secured adjacent to said letter board, said rack having notches which lie opposite the letters and symbols on said letter board, independent transversely movable frames, levers carried by said frames and adapted to be fitted into the notches in said rack and to be depressed to tilt said 130

letter board, and independent type disks, of type carried by said disks and adapted to be thrown into contact with said paper carriage, and devices operated by the tilting of said letter board for throwing said type into contact with said paper carriage, substantially as described.

12. The combination with a pivotally mounted letter board, and devices for tilting said letter board, of a shaft pivotally mounted in a vertical position independently of and adapted to be tilted in a direction at right angles to said letter board, and a rod connecting said shaft to said letter board, whereby by the tilting of said letter board the shaft will be tilted, substantially as described.

13. The combination with a pivotally mounted letter board, and a lever 19 connected to said letter board and projecting upward therefrom, of a shaft pivotally mounted in a vertical position and adapted to be tilted at right angles to said letter board, and a lever 26 connecting the lower portion of said shaft to the upper portion of said lever 19, whereby by the tilting of said lever the shaft will be tilted, substantially as described.

14. In a typewriter, the combination with a paper carriage, adapted to be moved transversely, and a rack on the lower portion of said carriage, of a shaft pivotally mounted in a vertical position opposite said carriage, devices for tilting said shaft, dog 97, having a tooth 98 adapted to fit into the spaces between the teeth of said rack, a recess 100 in the end of said dog, a spring for causing said tooth 98 to engage the rack, a pin 101 in said recess 100, and a slot 102 in said dog, adapted to receive the lower end of said shaft, substantially as and for the purpose specified.

15. The combination with a paper carriage, and a rack carried thereby, of a dog adapted to engage said rack, said dog provided with two teeth and an inclined surface between said teeth, a spring adapted to hold said dog in engagement with said rack, devices for throwing said dog out of contact with said rack, and a pin located between the teeth of said dog and engaging the said inclined surface, whereby when it is withdrawn from engagement with said rack it will be thrown laterally into position to engage one of the adjacent notches of the rack, whereby the carriage will be shifted laterally, substantially as described.

16. The combination with a transversely movable carriage, a rack carried thereby, a dog 97, having teeth 98 and 99, recess 100, and a pin 101 in said recess 100, of a pivot for said dog, a spring acting to force said tooth 98 into engagement with said rack and to shift said dog laterally, and a rod 105 for withdrawing said dog from engagement with said rack, substantially as described.

17. The combination with a paper carriage, a shaft pivotally mounted in a vertical position opposite said paper carriage, type disk carried by said shaft, small and capital let-

ters carried on the periphery of said disk, said small letters being placed beside the respective capital letters, and means for rotating said disk, of a letter board having letters and symbols marked thereon, said letter board being pivotally mounted, whereby it may be tilted, a transversely movable frame for operating said disk-rotating-devices, a lever carried by said frame, said lever being adapted to bear upon said letter board to tilt it when pressed downward, devices operated by said tilting of the letter board to tilt said shaft, whereby one of the letters carried by said type disk will be thrown into contact with the paper carried by said paper carriage, and devices for moving said letter board transversely to regulate the printing of small or capital letters, substantially as described.

18. The combination with a paper carriage, a shaft pivotally mounted in a vertical position opposite said paper carriage, type disk carried by said shaft, small and capital letters carried on the periphery of said disk, said small letters being placed beside the respective capital letters, and means for rotating said disk, of a letter board having letters and symbols marked thereon, said letter board being pivotally mounted, whereby it may be tilted, a transversely movable frame for operating said disk-rotating-devices, a lever carried by said frame, said lever being adapted to bear upon said letter board to tilt it when pressed downward, devices operated by said tilting of the letter board to tilt said shaft, whereby one of the letters carried by said type disk will be thrown into contact with the paper carried by said paper carriage, lever 60, having arms 62 and 63, spring for holding down said arm 63, lever 68 bearing upon said arm 62, finger board 71 connected to said lever 68, whereby by the depression of said finger board the letter board will be shifted transversely, substantially as and for the purpose specified.

19. The combination with a shaft 24 pivotally mounted in a vertical position and adapted to be tilted, a sleeve 27 mounted thereupon, a type disk 28 mounted on said sleeve, and a gear wheel 30 also mounted upon said sleeve, of a transversely movable frame 48, a lever 51 connected thereto, a rack frame 53 carried thereby and adapted to engage said gear wheel 30, a pivotally mounted letter board, and devices operated by the tilting of said letter board to tilt said shaft 24, substantially as and for the purpose specified.

20. The combination with a shaft 24 pivotally mounted in a vertical position and adapted to be tilted, a sleeve 32 mounted thereupon, a type disk 35 mounted upon said sleeve, and a gear wheel 36 connected to said sleeve, of a transversely movable frame 41, a rack frame 45 carried thereby and adapted to intermesh with the teeth of said gear wheel 36, a spring 47 connected to said frame 41, a plate 46 connected to said rack frame and projecting under said gear wheel 36, and a

lever 42 connected to said frame 55, whereby by depressing said lever said type disk 35 may be lifted, substantially as and for the purpose specified.

21. The combination with a carriage 77, a rod 80 carried thereby, and a paper cylinder 74 hinged upon said rod, of a plate 87 connected to said rod, a plate 89 supporting said plate 87, a track 86, and rollers 85 connected to the lower portion of said carriage 77 and adapted to run upon said track, substantially as described.

22. The combination with a carriage 77, a rod 80 carried thereby, and a paper cylinder 74 hinged upon said rod, of a plate 87 connected to said rod, a plate 89 supporting said plate 87, a track 86, rollers 85 connected to the lower portion of said carriage 77 and adapted to run upon said track, and a screw 90 mounted in said plate 89, adapted to bear against said plate 87 whereby the position of the carriage may be adjusted, substantially as described.

23. In a type writer, the combination with a base-board, a transversely movable carriage and a paper cylinder carried thereby, of devices for moving said paper carriage, types for printing upon the paper carried by said paper cylinder, a plate 89 extending from said base board in rear of the carriage, a plate 87, sliding transversely on the plate 89, and a set screw passing through the plate 89 and engaging the sliding plate 87 whereby the carriage is moved to or away from said types, substantially as described.

24. The combination with a transversely movable paper carriage, a shaft 24 pivotally mounted in a vertical position opposite said carriage, a sleeve 27 mounted upon said shaft, a type disk 28 and gear wheel 30 mounted upon said sleeve, a sleeve 32 mounted upon said sleeve 27, a type disk 35 and gear wheel 36 mounted upon said sleeve 32, type carried by said type disks, and a transversely movable frame 48, of a lever 51, a rack frame

53 carried by said frame 48, said rack frame 53 being adapted to intermesh with the teeth of said gear wheel 30, a transversely movable frame 41, a lever 42, a rack frame 45 carried by said frame 41, said rack frame 45 being adapted to intermesh with the teeth of said gear wheel 36, devices for lifting said gear wheel 36 when the lever 42 is depressed, a letter board 14, rack connected to said letter board, said rack being adapted to be engaged by said levers 42 and 51, rod 26 connecting said letter board with said shaft 24, whereby by tilting said letter board the shaft 24 will be tilted, devices operated by said shaft for shifting the position of the paper carriage transversely, a bar 106 connected to said carriage-shifting-devices, a finger board 71, devices connected to said finger board for shifting the letter board transversely, and devices for inking the type carried by said type disks 28 and 35, substantially as described.

25. In a typewriter, the combination with a carriage, a paper cylinder and a shaft on which said paper cylinder is mounted, of a rod pivoted in said carriage so that it may be thrown to or away from the paper cylinder, said rod being laterally movable and provided with an end to engage and disengage the shaft on which the paper cylinder is carried, substantially as described.

26. In a type writer, the combination with a paper cylinder, of a tilting type disk, a tilting letter board, devices connected with said tilting letter board and type disk for bringing said type disk into contact with the paper cylinder, a spacing mechanism, and a sliding bar connected with said spacing mechanism to engage the tilting letter board when the spacing mechanism is operated, whereby contact of the type disk with the paper cylinder is prevented, substantially as described.
